(57) **CLAIM**

The ornamental design for an electronic game machine, as shown and described.

DESCRIPTION

FIG. 1 is a front, bottom and left perspective view of an electronic game machine in accordance with our new design;

FIG. 2 is a rear, top and right perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, bottom and left perspective view of an electronic game machine illustrating another embodiment of our new design;

FIG. 10 is a rear, top and right perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof; and,

FIG. 17 is a front, top and left perspective view of the embodiment shown in FIGS. 9 through 16 in a state wherein left side covers are opened.
